UNITED STATES PATENT OFFICE.

PAUL A. DIETZ, OF FORT WORTH, TEXAS.

SKELETON STRUCTURE.

1,362,238.

Specification of Letters Patent. Patented Dec. 14, 1920.

Application filed October 25, 1919. Serial No. 333,293.

To all whom it may concern:

Be it known that I, PAUL A. DIETZ, a citizen of the United States, residing at Fort Worth, in the county of Tarrant and State 5 of Texas, have invented certain new and useful Improvements in Skeleton Structures, of which the following is a specification.

This invention pertains to skeleton structures.

The object of the invention is to provide a convertible structure which may be used to form a live stock shelter or other inclosure; or as a hay rack; or as a grain bin or 15 the like.

In carrying out the invention a plurality of vertical posts are suitably mounted and held upright. A horizontal frame is adjustably supported on the posts so as to be 20 fastened at different elevations. Joists are inclined from a central support which is also vertically adjustable and these joists have their lower ends resting on the frame. One of the features is that the frame, joists 25 and posts may be disassembled and reassembled in a different shape either by using the same parts or by adding additional parts.

The invention will be more readily understood from a reading of the following specification and by reference to the accompanying drawings, in which examples of the invention are shown, and wherein:

Figure 1 is a side elevation of a rectangular structure,

Fig. 2 is an elevation of the same, showing the frame and joists lowered, in dotted lines, to form a hay rack,

Fig. 3 is a detail of the joist socket,

Fig. 4 is a plan view of the same,

Fig. 5 is a plan view of one of the frame supporting collars,

Fig. 6 is a vertical cross section showing the structure as used in a grain bin,

Fig. 7 is a partial plan view of the parts converted into a hexagonal structure,

Fig. 8 is a plan view of the supporting collars,

Fig. 9 is a sectional detail showing the 50 manner of supporting the adjustable collars,

Fig. 10 is a side elevation of the inner post, showing a different form of adjustable connecting means between it and the upper bar,

Fig. 11 is a horizontal section through one of the outer or corner posts, showing in

elevation the adjustable attaching means, and,

Fig. 12 is an inner elevation of the same, with the bars removed.

In the drawings the numeral 10 designates an upright post, several of which are employed. Some of the posts are higher than the others and these are indicated by the numeral 10'. Each post rests on a disk or 60 circular plate 11 which may be of wood, concrete or other suitable material. An iron rod 12 is driven into the ground and projects up through the center of the plate. The rod in each case projects above the plate 65 and is received in a socket 13 in the center of the bottom of the post. The posts are thus supported above the ground and protected against decay and are held against displacement.

On each post 10 a vertically adjustable collar 14 is mounted. Each collar 14 has an outwardly directed annular flange 15. In Figs. 1, 2 and 6 the posts 10' are provided with adjustable collars 14', each having an outwardly directed annular flange 15'. In Fig. 7 a different style of collar 14^a is vertically adjustable on the post 10'. Each post has a series of holes 16 near its upper end and a second series 17 near its 75 lower end, the corresponding series of holes of the posts 10' being at a higher elevation than those of the posts 10.

A horizontal frame formed of beams or rails 18 is mounted on the posts 10. The 80 beams have their ends resting on the flanges 15 against the collar 14. The end of one beam overlaps the end of the other beam as is shown in Fig. 5. Each beam has a hook 19 which is engaged in an eye 20 on the collar. The collars are supported on pins 21 inserted in the holes 16 under the flanges. It is obvious that the collars may be raised 85 or lowered and the pins inserted accordingly, thus changing the elevation of the 90 frame.

A ridge timber 22 has its ends resting on the flanges 15' of the collars 14' and secured thereto by hooks 23 engaging eyes 24 (Fig. 8) on each side of the collars. The collars 105 14' may be adjusted vertically like the collars 14. Along each side of the ridge timber sockets 25 are disposed in suitable spaced order. These sockets receive heads 26 fastened on the upper ends of joists 27. 110 The heads are T-shaped in cross section so as to fit into the sockets, but to be readily re-

movable therefrom. The joists incline downward from the timber 22 and rest on the beams 18 of the horizontal frame, the ends of the joists overhanging the beams 5 and constituting eaves.

After the frame and joists are in place brace rods or connections 28 may be stretched from the corner posts to eye-stays 29 either fastened to one of the plates 11 or 10 driven into the ground, at points centrally between said posts. These connections may include turn-buckles 30. It is obvious that the skeleton structure may be used advantageously in many ways. For instance by 15 covering the joists in any suitable way to form a roof, a livestock shelter or canopy is had; sides and ends may be added if desired and a complete building had. By removing the pins 21 and lowering the collars 20 14 and 14' to the position shown in dotted lines in Fig. 2, the frame and joists are lowered. This arrangement provides an excellent hay rack and the hay stacked on the lowered joists is supported above the 25 ground, permitting a free circulation of air thereunder. A foraminous ventilating column 31 may be placed along the ridge timber and the hay stacked therearound and ventilated. Curing under these conditions 30 would be superior.

It will be seen that the beams, posts and the ridge timbers may be easily disassembled and ridge timbers and beams of different lengths used to build structures of different sizes.

In Fig. 7 I have shown a structure exhibiting an octagonal shape in plan, the same parts being used except the ridge timber and more beams being added. A central 40 pole 10' is employed and sockets 25' similar to the sockets 25 are provided on the collar 14^a for receiving the heads 26. Other shapes could be made and various kinds of shelters formed.

45 In Fig. 6 I have shown a grain bin structure in which two sets of frames and joists are used, one forming the floor support and the other the roof support. Foraminous material, such as screen, is used to form a 50 floor 40 and sides 41. The central column 31 is used and additional foraminous columns 42 are mounted on the floor and extend to the roof joists 27. These columns 42 may assume any suitable cross-sectional 55 shape and may be made in any suitable manner. By placing them between the sides 41 and the central column the grain will be thoroughly ventilated by the air which will enter through the floor 40. Grain or roots 60 may be stored in this structure. A suitable roof (not shown) is placed on the upper joists.

It is obvious that the frame timbers 22 could be supported in various ways and the 65 collars and holes eliminated. In Figs. 10,

11 and 12 I have shown plates 50 mounted on the posts, each plate having sockets 51 at different elevations, said sockets being similar to the sockets 25. The timbers 22 have T-shaped heads 52 at each end engaging in sockets on the posts 10. It will be seen that the timbers are vertically adjustable and easily placed in position.

It is pointed out that the rods 12 hold the posts against lateral displacement, while 75 the braces 28 hold the structure against upward displacement and at the same time make it rigid and substantial. The flexibility of the structure will be readily appreciated and its many uses and advantages 80 are obvious.

What I claim is:

1. In a skeleton building structure, a plurality of assembled upright posts, collars vertically adjustable upon the posts, and 85 having laterally extending flanges, substantially horizontal beams arranged in contact with the collars and supported by the flanges, detachable elements connecting the beams and collars, joists arranged at an incline and supported near their ends by the beams, an inner support, and sockets secured to the inner support, and heads carried by the joists and adapted for insertion within the sockets. 95

2. In a skeleton building structure, a plurality of assembled upright posts, collars vertically adjustable upon the posts and having laterally extending flanges, substantially horizontal beams arranged in contact 100 with the collars and supported by the flanges, detachable elements connecting the beams and collars, joists having their outer ends arranged upon and supported by the beams, an inner vertically adjustable support, and means for detachably connecting the inner ends of the joists with the inner support. 105

3. In a skeleton building structure, a plurality of outer upright posts arranged in 110 suitable order, collars vertically adjustable upon the posts and having laterally extending flanges, substantially horizontal beams arranged in contact with the collars and supported by the flanges and forming an 115 outer frame, detachable elements connecting the beams and collars, a plurality of inner upright posts, collars vertically adjustable upon the inner posts and having laterally extending flanges, an inner horizontal beam 120 supported by the flanges of the last named collars, detachable elements connecting the collars and last named beam, joists having their outer ends arranged upon the outer beams, a plurality of sockets carried by 125 the inner beam, and a plurality of heads secured to the inner end of the joists and adapted for insertion within the sockets.

4. In a skeleton building structure, a plurality of assembled upright posts, collars 130

- vertically adjustably mounted upon the posts and having laterally extending flanges, substantially horizontal beams arranged in contact with the collars and supported by the flanges, detachable elements connecting the beams and collars, joists having their outer ends supported by said beams, a plurality of inner upright posts, an inner horizontal beam, vertically adjustable means for connecting the inner horizontal beam and the inner posts, and means for detachably connecting the inner ends of the joists with the inner horizontal beam.
- 5 5. In a skeleton building structure, a plurality of assembled outer upright posts, a plurality of horizontal beams extending
- about the posts and forming an outer frame, vertically adjustable means for detachably connecting the beams and the posts, a plurality of inner upright posts, an inner horizontal beam extending between the inner posts, vertically adjustable means for detachably connecting the inner beam and inner posts, a plurality of joists having their outer ends arranged upon and supported by the outer beams, a plurality of sockets carried by the inner beam, and a plurality of heads secured to the inner ends of the joists and adapted for detachable engagement within the sockets.

In testimony whereof I affix my signature.

PAUL A. DIETZ.
